CLAIM

The ornamental design for a dog biscuit, as shown and described.

DESCRIPTION

FIG. 1 is a top perspective view of a dog biscuit;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in FIGS. 1, 2, 4–7 illustrate portions of the dog biscuit that form no part of the claimed design.
